UNITED STATES PATENT OFFICE.

JOSEPH V. HOTCHKISS, OF JAY, INDIANA.

PULLING DEVICE.

SPECIFICATION forming part of Letters Patent No. 436,000, dated September 9, 1890.

Application filed April 15, 1890. Serial No. 348,067. (No model.)

To all whom it may concern:

Be it known that I, JOSEPH V. HOTCHKISS, a citizen of the United States, residing at Jay P. O., in the county of Switzerland and State 5 of Indiana, have invented certain new and useful Improvements in Devices for Moving Wrecked Cars, Pulling Stone-Cuts from Ledges, Moving Houses, Pulling Stumps, &c.; and I do declare the following to be a full, 10 clear, and exact description of the invention, such as will enable others skilled in the art to which it appertains to make and use the same, reference being had to the accompanying drawings, and to the letters of reference 15 marked thereon, which form a part of this specification.

The special object of the invention is to make a machine adapted for elevating stone and other heavy articles, moving houses, 20 pulling stumps, and serving as a derrick in stone-quarries.

Figure 1 of the drawings is a perspective view, and Fig. 2 a longitudinal vertical section on a smaller scale.

25 In the drawings, A represents the base, on which at one end are erected the posts B B, connected by a cross-bar, the said posts B B and bar B' forming a frame for the windlass C. The latter, as well as the crank-shaft D, 30 has bearings in the said posts, the windlass being provided with a spur-wheel E and crank-shaft D, with a pinion E', so that the pinion may mesh with and rotate the spur-wheel.

35 F is a cable, whose two ends are made fast in rings f f on the opposite sides of the upper end of the lever G, then is coiled around the windlass C, and then passes under the base-rollers H H and up over a roller I, trunnioned be- 40 tween the posts J J, which rise up on an incline from the base A and are connected at the top by a cap-bar K. The lever G is fulcrumed on a shaft L, which has its bearings a' on the base-beams a a and is provided on each side with a fast ratchet M and a fast 45 concave pulley N, the ratchet-wheels M being turned by the pivoted pawls g g, one on each side of the lever.

50 O is the drag rope or chain, which has one end made fast to the periphery of each pulley N and its middle provided with a grapping-hook P. It will thus be perceived that the pulleys N N, which wind up the drag-rope O and the ratchets M M, are both fast

on the same shaft L, while the lever G turns 55 loosely thereon, and by means of its pawls g g turns the shaft L from right to left, as shown in the drawings. This turn is, however, only for a short distance, where it is held by the detent-pawls g', while the lever 60 G is carried back to take another hold, when it is again pulled to the left, and so on until the work is done. Now, the means which I employ to actuate the lever G in both directions are the cable F on the rolls H H I and 65 the windlass mechanism operated by hand. By being properly fastened down at the base and the grapple connected with a stump or with a tree it may be pulled up by the roots, or a house on rollers may be moved. By 70 causing the drag-rope O with its grapple to pass over the roller I heavy weights may be lifted with great convenience.

The grapple shown in the drawings is for pulling stone-cuts from a quarry-ledge, the 75 chain being run direct from the drum through a ring and then double to the stone on which the grapple is hooked. For pulling houses on rollers or any other heavy weight the chain is passed directly from the drum to the 80 house and attached thereto, or may be first passed over the upper pulley, as may be preferred.

Having combined this mechanism to multiply power at the expense of velocity, one 85 man is enabled to draw or lift a heavy weight; but I may employ any suitable power, according to the work to be done.

What I claim as new, and desire to protect by Letters Patent, is— 90

The combination, with a frame, substantially as described, of the windlass C, connected by the spur-wheel E and pinion E' with the crank-shaft D, the cable F, the lever G on a shaft L, the base-rollers H H, the elevated roller I, the ratchet-wheels M M, pulleys N N, and drag-rope O, provided with a grapple P, said ratchet-wheels being mounted on and carried by the shaft L, whereby the whole may be conveniently used, for the purposes set forth. 95

In testimony whereof I affix my signature in presence of two witnesses.

JOSEPH V. HOTCHKISS.
